Primary Examiner — Anhdao Doan(74) *Attorney, Agent, or Firm* — Banner & Witcoff, Ltd.(57) **CLAIM**

The ornamental design for a x-ray tube for medical use, as shown and described.

DESCRIPTION

FIG. 1 is a perspective view of a x-ray tube for medical use showing our new design,

FIG. 2 is a front elevational view thereof,

FIG. 3 is a rear elevational view thereof,

FIG. 4 is a top plan view thereof,

FIG. 5 is a bottom plan view thereof; and,

FIG. 6 is a left side elevational view thereof, a right side elevational view being a mirror image thereof.

The broken lines illustrate portions of the x-ray tube for medical use that form no part of the claimed design. The broken lines form no part of the claimed design.
